UNITED STATES PATENT OFFICE.

MARY LOUDON SCHOONMAKER, OF RONDOUT, NEW YORK.

CLOTHES-HANGER.

No. 843,633.

Specification of Letters Patent.

Patented Feb. 12, 1907.

Application filed May 16, 1906. Serial No. 317,117.

To all whom it may concern:

Be it known that I, MARY LOUDON SCHOON-
MAKER, a citizen of the United States, and
residing at Rondout, in the county of Ulster
5 and State of New York, have invented cer-
tain new and useful Improvements in Clothes-
Hangers, of which the following is a specifica-
tion, such as will enable those skilled in the
art to which it appertains to make and use
10 the same.

This invention relates to devices for hang-
ing clothes in closets, cupboards, halls, and
the like; and the object thereof is to provide
15 an improved device of this class which is sim-
ple in construction and operation and by
means of which various kinds and classes of
clothing may be conveniently suspended or
supported by means of a single device which
20 may be attached to or connected with a pole,
bar, or other support.

The invention is fully disclosed in the fol-
lowing specification, of which the accompany-
ing drawing forms a part, in which the sepa-
25 rate parts of my improvement are designated
by suitable reference characters in each of
the views, and in which—

Figure 1 is a front view of my improved
clothes-hanger and showing one method of
its use, and Fig. 2 a view at right angles to
30 that of Fig. 1.

In the practice of my invention I provide
a rod *a*, the upper end of which is provided
with a hook, ring, or eye *b* and the lower end
with a hook *c*, and said rod *a* is provided with
35 a plurality of radially-projecting arms *d*,
which in the form of construction shown are
all in the same vertical plane and which pro-
ject outwardly from the rod *a*, and each of
said arms *d* is provided at its outer end with
40 a hook member *d*², and said arms increase in
length from the bottom upwardly. The rod
a is also provided in the form of construction
shown with two laterally-directed arms *e*,
which are secured thereto or connected there-
45 with near the top thereof and which range
outwardly and upwardly and are preferably
provided with knob or head members *e*² and
which are intended as a support for hats,
while the arms *d* and hook *c* at the lower end
50 of the rod *a* are intended as a support for va-
rious articles of clothing, and by reason of
the fact that the arms *d* all increase in length
from the bottom of the rod *a* upwardly va-
rious articles may be conveniently hung on

the hook *c* and the separate arms *d* without 55
said articles interfering with each other.

The arms *e* may be in a plane with the rod
a, as shown in full lines in Figs. 1 and 2, or
they may be extended outwardly and up-
wardly, as indicated in dotted lines in Fig. 6a
2. Secured to the rod *a*, near the bottom
thereof, in the form of construction shown
is a transverse member *f*, which in the form
of construction shown is composed of wire
having backwardly-directed end loops which 65
are adapted to bear on a wall *g*, which is also
provided with a transverse strip *h*, from
which the hanger is suspended by means of
a screw, hook, or other device *i*, the object
of the part *f* being to hold the hanger in a 70
vertical plane parallel with the wall, and any
suitable transverse device which will accom-
plish the same object may be employed for
this purpose, and in some cases my improved
clothes-hanger may be employed without 75
the part *f*, said hanger being suspended by
means of a hook, nail, or other device se-
cured directly to a wall or other support, and,
if desired, any suitable means may be pro-
vided to prevent the bottom of a hanger from 80
swinging laterally.

My improved clothes-hanger may be made
of any desired material, metal being pre-
ferred, and any desired number of the arms
d and *e* may be employed. 85

Having fully described my invention, what
I claim as new, and desire to secure by Let-
ters Patent, is—

A clothes-hanger, comprising a main rod
having a hook, ring or eye at its upper end 90
and a forwardly-directed hook at its lower
end, forwardly-directed arms connected with
said main rod between the top and bottom
thereof and provided at their free ends with
hooks, said arms increasing in length up- 95
wardly from the bottom of the main rod to
the top thereof, and said main rod being also
provided at the upper end thereof with out-
wardly and upwardly directed arms.

In testimony that I claim the foregoing as 100
my invention I have signed my name, in pres-
ence of the subscribing witnesses, this 14th
day of May, 1906.

MARY LOUDON SCHOONMAKER.
